CLAIM

The ornamental design for a rear lamp on vehicle body, as shown and described.

DESCRIPTION

FIG. 1 is a front view of a rear lamp on vehicle body showing our new design;

FIG. 2 is a right view thereof;

FIG. 3 is a top view thereof;

FIG. 4 is a bottom view thereof;

FIG. 5 is a rear view thereof;

FIG. 6 is a left view thereof; and,

FIG. 7 is a perspective view thereof in context.

The overexposed or faded features of the motor vehicle exterior are provided for the purpose of illustrating portions of the article that form no part of the claimed design.
